KNOB FOR A DOOR LOCK

Van Day Truex, New York, N. Y., assignor to The Yale
& Towne Manufacturing Company, Stamford, Conn.,
a corporation of Connecticut

Application April 30, 1956, Serial No. 41,250

Term of patent 7 years

(Cl. D50—3)

Fig. 1.

Fig. 2.

Fig. 1 shows a face view of a knob for a door lock, showing my new design.

Fig. 2 is a top plan view of Fig. 1.

The characteristic feature of the doorknob resides in the ornamental pattern on the face thereof.

I claim:

The ornamental design for a knob for a door lock, substantially as shown and described.
